UNITED STATES PATENT OFFICE.

CHARLES EDW. SEARCH, OF MILWAUKEE, WISCONSIN.

PROCESS OF AND OVEN FOR HEAT TREATING OBJECTS.

Application filed April 17, 1922. Serial No. 553,454.

To all whom it may concern:

Be it known that CHARLES EDWIN SEARCH, a citizen of the United States of America, residing at Milwaukee, in the county of Milwaukee and State of Wisconsin, has invented a certain new and useful Process of and Oven for Heat Treating Objects, of which the following is a specification.

This invention relates to an oven and the process of using same in the fabrication or production of objects requiring heat to bring them to a state of perfection for use. The invention, as it has been developed, has been made in connection with what is known as a "core oven," an oven designed for the heating and drying out of cores as well as for the heating and drying out of formed molds. But the invention is not limited to "core ovens", but is applicable to brick making, ceramics, etc., and while the description herein may be specific it is intended to apply generally. These core ovens have for their object the production of dry cores or molds so that the castings made from them are of better quality and not so liable to be chilled in places and thus more liable to breakage. The ordinary form of core oven is arranged horizontally with a door at one end opening into the core room, and it is provided with a car movable upon rails so as to transport the cores or molds loaded thereon from the core room or foundry into the oven to be heated. This usual arrangement is exceedingly wasteful of space, for it necessitates a place for making the cores or molds, a place for loading same on the carriage, a place, an oven itself, for heating same, and a place for pouring the dried molds or those made up from the dried cores. This prior art therefore it will be observed, uses a four place floor space.

The present invention has for its object the saving of valuable space as compared with prior practice. It contemplates the forming of molds or cores at one place, the loading of same onto a platform at a second place, the lowering of this platform into a pit oven, not requiring other floor space, and the transport of the heated cores or molds to a third place for use as by casting.

A further object of this invention is the provision of an oven so located in a floor pit, as to necessitate no considerable height above the floor at the pit for crane clearance.

55 A further object of the invention is the practicing of the art of preparing objects

by heating, in such a way that the workmen are always at the floor lever while doing their work on the said objects.

Further objects of the invention are in 60 matters of detail and will be pointed out in the appended claims.

This invention will now be described in connection with the accompanying drawings forming a part of this specification and in 65 which like characters are used in the different views to represent the same or similar parts, and in which

Fig. 1 is a transverse vertical sectional view of the oven taken on the line I—I, 70 Fig. 2.

Fig. 2 is a plan view partly in section at the level of the burners.

Fig. 3 is a vertical sectional view, taken on the line III—III, Fig. 2, of the castings 75 on top of the oven wall, and showing the cover plates.

Fig. 4 is a vertical sectional view of the same, taken on the line IV—IV, Fig. 2.

Fig. 5 is a schematic plan view of the upper flue castings lying on the oven wall and of the central bridge piece across the oven, showing the draft connection to a motor operated fan and to a chimney.

Fig. 6 is a fragmentary sectional plan view 85 of a corner portion of the oven wall.

Fig. 7 is a fragmentary elevation of a corner of the elevator platform.

In the description of the invention, the term "matrices" will be used to represent 90 the more cumbersome terms "cores or molds", and of course, as indicated above, bricks, ceramic objects, etc., would be the equivalent.

The floor level 1 is formed with a pit 2 lined with a wall 3 made of fire brick. This wall 3 is reinforced by a structural steel frame 4 and plates 41 surrounding the same, the structural steel being comprised of two horizontal frame belt portions surrounding 100 the oven at places more clearly indicated in Fig. 1 by the location of the two horizontal sets of square washers, 6. The frame 4 is further comprised of vertical sections of structural steel lying below, between and 105 above the two horizontal surrounding belt portions, this sectional construction accommodating relative expansion between the wall 3 and its reinforcement without danger of shearing of the retaining bolts. This 110 frame structure is held in place by bolts 5 and washers 6 on the inner face of the oven

wall. The reinforcement is further comprised of metal guides 8 having a different ratio of expansion than the wall 3 and held in place by bolts 7 extending therefrom and 5 through the wall 3 and frame 4, with substantial clearance where they pass through the wall. These guides 8 may expand relatively to the wall 3 without damaging the bolts 7 by virtue of the clearance thus provided. A cylinder 9 extends downwardly into a recess at the bottom of the pit and is securely mounted therein. A pipe 10 supplies oil or water under pressure to the cylinder and exhausts the same therefrom. 10 A plunger 11 is mounted to reciprocate within the cylinder 9 and is properly packed by means of the gland 12 and packing 13 in the usual manner. A platform 14 is mounted upon the head of the plunger and 15 forms the bottom of the effective oven space. A rib 15 extends downwardly from the bottom of the platform near its outer edge and coacts with a sand seal 16 provided at the bottom of the pit directly adjacent the 20 oven walls. This platform 14 is preferably made in sections bolted together as clearly shown in Fig. 2 and is made strong by means of reinforcing ribs. The spaces between the ribs may be filled with sand and the top 25 faced off with fire brick, with the object in view to prevent the heat from having access to the hydraulic parts below. The platform 14 is provided with adjustable slides 30 17 fitting into notches at the corners 35 of the platform at its top edge. These slides are fastened in place by cap screws 18 which fit loosely through holes 181 formed in the slides and these slides 17 are adjustable by means of cap screws 19 screwed 40 through the side of the elevator platform as clearly shown in Fig. 7.

At the top of the oven are placed castings 45 20, 21, 22, two of which, 20, 22, are U-shaped wall castings which abut at their ends the respective sides of the casting 21 which extend across the oven in the nature of a mid beam or runway. These castings 20, 21, 22 are hollow and form flues for taking off the gases from the oven. The 50 arrangement of the flues is clearly shown in Fig. 5 where it will be seen that the two walls castings 20, 22 have upper outlets 26 for the gases, these being formed in two of the inner sides thereof, but of course they 55 may be formed also on the third inner side. The middle casting 21 has upper outlets 261 formed in its bottom, and it will be noted that the three castings 20, 21, 22 have their flue functions entirely independent, leading 60 off respectively by the pipes 33, 34, 35 to a pipe 36 which connects to fan 31 operated by a motor 32 or by means of pipe 37 directly to chimney 38. The fan discharge 311 also connects to the chimney 38. 65 Lower outlets 27, 28 are also provided in

two opposite walls of the oven, and one of these, 27, connects with a vertical flue 29 extending up the wall and connecting at the top by outlets 291 with the flues of wall castings 20, 22. The other lower outlets 70 28 extend directly through the oven wall and are connected to pipe 36, one of the connections being shown in Fig. 5 by means of pipe 30. Dampers 331, 341, 351 are provided for pipes 33, 34, 35 leading from the 75 flues. Dampers 361, 371, 301 are respectively provided for pipes 36, 37, 30, leading to the fans and chimney.

The upper outlets 26, 261, connecting with the flues of castings 20, 21, 22 may be selectively stopped off by means of metal covers 262 fastened in place in any convenient manner. One of these covers 262 is shown in place at the left of Fig. 3 but it is intended that other of these upper outlets 26 may be similarly closed off as may be found necessary or desirable under different conditions of operation.

Near the bottom of the oven space and just above the level of the platform in its lowermost position are provided burners 39 functioning through opposite walls of the furnace, three on a side, as clearly indicated in Figs. 1 and 2. These burners are indicated as ordinary oil burners but of course other heating means may be used such as coal or gas. It is preferable to have the heat developed directly within the oven, with oil or gas burners.

Top castings 23 are preferably provided to lie above wall castings 20, 22 so as to insulate same at the floor level as may be seen from Fig. 4 but of course a top casting may similarly be provided for casting 21. These top castings 23 are provided with a sand seal along their inner edges as is also casting 21 as shown. Cover plates 24 are provided, three edges of two of which lie in the sand seal of the top casting 23 and middle casting 21. The third cover plate 24, three of these cover plates being shown at each side of middle casting 21, has two opposite edges in the sand seal of top casting 23 and middle casting 21, and the remaining opposite edges thereof lie in matched recesses in the two cover plates already in place. Any other arrangement, of course, can be provided that would suitably close off the top of the oven.

The operation and practice of this invention is as follows:

The elevator platform 14 is brought to its uppermost position adjacent the floor level and closely underneath the mid beam casting 21. In this position, formed matrices are placed thereon in a tier and as they are placed thereon, easily accessible to the workmen from all sides by reason of the mid beam casting 21 extending across the top of the pit, the necessary operations are con- 130

veniently performed such as blacking, brushing, slicking, etc. After this tier of matrices has been completed and dressed, the elevator is lowered to a position to bring this tier 5 just below the floor level and a second tier of matrices is loaded upon the platform, suitable plates being provided to rest upon the first tier of matrices, or suitable racks may be provided to support the second tier 10 directly from the platform by extending the racks down to the platform between the matrices of the first tier. This matter of support is an unimportant detail and may be accomplished in any desired manner, the 15 essential point being that the matrices are loaded upon the elevator platform in tiers, so as always to have the dressing and loading at the floor level. After the second tier is lowered and dressed a third tier may also 20 be similarly placed thereon and dressed, and so on until the elevator is completely loaded when in its lowermost position. The cover plates are now placed over the oven, completely closing same. The burners 39 are 25 now lighted and for a time the hot gas injected into the oven from the burners is drawn off through the flues leading from the upper outlets 26, 261. These flues deliver to pipes 33, 34, 35 and thence to pipe 36 de- 30 livering to the inlet of fan 31 the discharge 311 of which passes to chimney 38. After a time it may be found advisable to close off the flues leading from the outlets; this may be done by closing off dampers 331, 341, 35 351. These may be separately or collectively closed off. If they are all closed off, it becomes desirable to have some other outlet for the gases, and in such case, damper 301 may be opened up so as to be able to discharge the 40 hot gases from the lower outlets 28, through the pipe 30, see Fig. 5. This then provides for a discharge of the hot gases either from the top of the oven or from the bottom thereof. Another alternative provision for dis- 45 charging the gases is by passing same through the fan or around the same to the chimney. The former may be accomplished by opening damper 361 of pipe 36 and closing damper 371 of pipe 37, the direct dis- 50 charge to the chimney being accomplished by a reversal of these damper positions.

After the matrices are thoroughly heated and dried, and this has been found to take about one-third the time ordinarily consumed with the horizontal type of furnace, the matrices are removed by a reverse series of steps to that of the loading; that is, the cover plates having been removed from the top of the oven, the elevator platform is raised so that the last tier of matrices placed thereon is at or adjacent the floor level. This tier being removed, the elevator platform is again raised to bring the next tier at or adjacent the floor level and then this is 55 removed, and so on.

It will be seen that in the practice of this invention both time and space are saved and the workman are at all times operating near the floor level.

It should be understood that it is not de- 70 sired to limit the invention to the exact steps of the process described or to the exact details of construction of the apparatus shown and described, for obvious modifications will occur to persons skilled in the art. 75

It is claimed and desired to secure by Letters Patent:

1. An oven comprising a platform vertically adjustable to different levels and having its upper limit of adjustment adjacent 80 the floor level, and a stationary beam extending across said platform at the floor level.

2. In combination, a pit oven, an elevator platform therein, a plunger for operating 85 said platform, and a sand seal between said platform and pit wall.

3. In combination, a pit having its opening at the floor level and forming an oven chamber, an elevator platform in said pit, 90 means for adjusting said platform to various levels and adjacent the floor level as a limit, and means for permitting crossing of said pit at the floor level at all times. 95

4. The process of fabricating objects comprising loading a platform adjacent the floor level with a tier of formed objects, dressing said objects, lowering said platform into a pit until the top of said tier is adjacent the floor level, further loading said 100 platform with a second tier of formed objects, dressing said second tier, lowering said platform farther into said pit to bring said second tier below the floor level, covering said pit, applying heat to said objects, 105 uncovering said pit, elevating said platform to its second position, removing said second tier of objects, elevating said platform to its original position and removing said first tier of objects. 110

5. The process of fabricating matrices comprising forming matrices at a selected place, transporting formed matrices to a second selected place, dressing said matrices at said second place at the floor level, lowering said matrices immediately below said floor level, placing other said formed matrices immediately above said lowered matrices, dressing said other matrices, 120 lowering all of said dressed matrices, confining same within a chamber at said second place, drying same by heating within said chamber, elevating same, and removing same to a third selected place for use. 115

6. In an oven, means forming a chamber, 125 a platform within said chamber, said means and said platform being relatively vertically movable, means for delivering heating medium into the bottom portion of said chamber, and means for effecting discharge 130

of said medium from the upper side and central portions of said chamber.

7. In an oven, means forming a chamber, a platform within said chamber, said means and said platform being relatively vertically movable, means for delivering heating medium into the bottom of said chamber at opposite sides thereof, and means for effecting discharge of said medium from the bottom and top portions of said chamber, said bottom discharge means being located at the chamber sides other than those containing said delivery means.

8. In an oven, means forming a chamber, a platform vertically movable within said chamber, means for delivering heating medium into said chamber adjacent to said platform when the latter is in its lowermost position, and means for effecting discharge of said medium from upper side and central portions of said chamber.

9. In an oven, means forming a chamber, a platform vertically movable within said chamber, means for delivering heating medium into said chamber adjacent to said platform when the latter is in its lowermost position, means for effecting discharge of a part of said medium from a lower portion of said chamber, and means for effecting discharge of the remainder of said medium from an upper portion of said chamber.

10. In an oven, means forming a chamber, a platform vertically movable within said chamber, means for delivering heating medium into a bottom portion of said chamber, means for effecting discharge of said medium from lower and upper portions of said chamber, and means for effecting closure of certain of said discharge effecting means.

11. In an oven, means forming a chamber, a platform vertically movable within said chamber, means for delivering heating medium into a lower portion of said chamber, conduit means spanning the upper portion of said chamber, and means for effecting discharge of said medium through said conduit means.

12. In an oven, means forming a chamber, a platform vertically movable within said chamber, means for delivering heating medium into a bottom portion of said chamber, means for effecting discharge of a portion of said medium from a lower portion of said chamber and at the sides thereof other than those at which said heating medium is admitted, and means for effecting discharge of the remainder of said medium from upper side and central portions of said chamber.

13. In an oven, a wall of one material, a

guide of another material having a different ratio of expansion, bolts penetrating said wall and connecting said wall and guide, a platform movable within said oven and co-acting with said guide, and means providing for relative expansion of said wall and guide without liability of shearing said bolts.

14. In an oven comprising a vertically adjustable platform, the combination of a side wall, a metal structure reinforcing said wall, and a vertical guide for said platform supported by said structure.

15. In an oven comprising a vertically adjustable platform, the combination of a side wall, a metal structure reinforcing said wall, and a vertical guide for said platform supported by said structure, and an adjustable slide on said platform coacting with said guide.

16. An oven comprising a floor pit and an elevator platform bottom, and a stationary beam extending across the pit at the floor level.

17. An oven comprising a floor pit and an elevator platform bottom, and a beam extending over the pit at the floor level, said beam being hollow and serving as a flue.

18. In an oven comprising a floor pit means for heating same by injected hot gases, an exhaust gas flue adjacent the floor line and means for insulating said flue at said floor level.

19. In combination with an oven heated by entering hot gases, an exhaust outlet for said gases, a fan suction-connected to said outlet, a chimney connected to said outlet, and means for interchangeably withdrawing said gases by said fan and chimney.

20. In combination, an oven comprised of brick side walls, a plate coacting with the exterior of each of said walls, and reinforcing structure surrounding and uniting all of said plates.

21. In an oven comprising a vertically adjustable platform, the combination of a side wall, metal structure reinforcing the outside of said wall, and a vertical guide for said platform supported by said structure on the inside of said side wall.

22. In an oven comprising a vertically adjustable platform, the combination of a side wall, metal structure reinforcing the exterior of said wall, a vertical guide for said platform supported by said structure adjacent the interior of said side wall, and an adjustable slide on said platform co-operable with said guide.

In testimony whereof the signature of the inventor is affixed hereto.
